UNITED STATES PATENT OFFICE.

MILTON W. BROWNE, OF KANSAS CITY, MISSOURI.

DEFROSTER FOR REFRIGERATING PLANTS.

Application filed January 9, 1926. Serial No. 80,387.

The present invention relates to improvements in means for depositing refrigerant pipes or coils in cold storage plants, packing houses and other refrigerated rooms or compartments, and especially those wherein perishable food products are stored.

The primary object of the invention is to provide novel and improved means whereby conservation of refrigeration is possible, it enabling the refrigerant pipes to be kept free of frost and frozen mixture, or substantially so, in refrigerated rooms of all kinds whereby the full benefit and efficiency of the refrigeration may be obtained and the accumulation of excessive frozen moisture may be promptly and economically removed, with the result that the refrigerating machinery may be operated at the minimum instead of the maximum capacity in order to obtain and maintain the proper refrigeration and temperature in such rooms.

To these and other ends, the invention consists in certain improvements and combinations and arrangements of parts, all of which will be hereinafter more fully described, the features of novelty being pointed out particularly in the claims at the end of the specification.

In the accompanying drawing:—

Figure 1 is a view of a defroster constructed in accordance with the preferred embodiment of the invention;

Figure 2 represents, on an enlarged scale and in axial section, the cutter member and the guard which is preferably associated therewith;

Figure 3 represents an end view of the cutter member, on an enlarged scale, and looking toward the right in Figure 1; and

Figure 4 is a fragmentary view showing in perspective a portion of one of the cutters.

Similar parts are designated by the same reference characters in the several views.

According to the present invention, the refrigerant pipes within refrigerated compartments or rooms can be maintained in a clean condition or substantially free from frost and frozen mixture, thereby insuring maximum refrigeration efficiency of the refrigerant pipes, as the even and unvarying refrigeration through the refrigerant pipes may be uniformly maintained without interruption, and with maximum efficiency although at a minimum of its capacity to effect the required amount of refrigeration, with a corresponding reduction in the expense of

operation; and these results may be obtained without the necessity of shutting down the refrigeration and without the necessity of chopping or hammering the frost and frozen mixture from the refrigerant pipes and the attendant expense and objections to such methods.

The defroster, according to the present invention, comprises a cutter member 1 and operating means therefor which preferably comprises a portable electric motor 2 which is suitably coupled or attached to the cutter member. The cutter member comprises a suitable number of knives or cutting blades 3 which are spaced around the circumference of the cutter member and they also preferably have a pitch so that they extend in a direction helically of the circumference thereof. As shown, for example, each knife or cutter blade has a twist whereby it extends around half the circumference of the cutter member as it proceeds from one end attached to one end of the cutter member to the other end thereof which is attached to the other end of the cutter member. The knives or cutter blades may be secured at their ends in different ways. Preferably, and as shown, the ends of the blades are fixed to the outer ends of arms 4 and 5 which project radially from hubs 6 and 7, the latter being keyed or otherwise fixed to a supporting sleeve or tube 8. Each knife or cutter blade is of relatively shallow thickness, measured in a direction radially of the cutter member and it has a sharp preferably continuous cutting edge 3a which, as shown in Fig. 4, is formed by two surfaces, one of which is a surface of revolution and the other is dished and merges into the first-mentioned surface, the dished surface forming a frost discharge means.

The cutter member is used by placing its circumference formed by the circumferentially spaced knives against the refrigerant pipes or coils to be defrosted, with the axis of the cutter member arranged transversely of the length of the pipe, and where the pipes or coils are arranged in closely spaced rows, the cutter member is interposed between the pipes of the adjacent rows so that it may act simultaneously thereon. While the cutter is held against the pipe or pipes to be defrosted, the cutter is revolved in a direction to cause the edges 3a of the knives to move forwardly and to thereby cut through the frost or frozen mixture on the pipes by a

movement of the cutting edges in a direction substantially parallel to the surface of the pipe, thus detaching the frost or frozen mixture therefrom; and as the removal of the frost or frozen mixture progresses, the cutter member is shifted or moved forwardly along the pipe or pipes to effect the removal of the frost or frozen mixture throughout the length of the pipe or pipes. Owing to the shallow thickness of the knives or cutter blades in a direction radially of the cutter member, each knife or cutter member is enabled to cut into the frost or frozen mixture with minimum obstruction therefrom, and the frost or frozen mixture detached by the knives is free to discharge past the inner side of the knives, thus facilitating the discharge of the detached frost or frozen mixture and avoiding clogging of the cutter member. Preferably, the cutter member tapers in diameter from one end toward the other, the cutting edges of the knives being arranged spirally in the surface of the cone, as shown, so that one end of the cutter member will be smaller in diameter than the other, thus facilitating the insertion of the cutter member into the spaces between rows of refrigerant pipes or adjacent convolutions of refrigerant coils.

30 A guard is preferably provided to protect the knives or cutter blades during handling of the defroster. In the present instance, a cage-like guard which may be constructed of wire or similar material is employed, it comprising rings 9 and 10 which are connected by longitudinally extending members 11, and the rings are connected by spokes or rods 12 and 13 to hubs 14 and 15, the latter being loosely mounted on the sleeve 8 immediately outside of the hubs 6 and 7. The rings 9 and 10 of the guard are of sufficient diameter to permit the cutter member to revolve freely within the guard and, hence, the guard will not interfere with the operation of the cutter member.

Different means may be employed for revolving or operating the cutter head. Preferably, a small portable electric motor 2 of the type adapted to operate from current taken by a cord extension 2^a from ordinary alternating or direct current lighting or power service systems is employed, the motor being preferably equipped with a handle 16 which serves as means for carrying and manipulating the defroster. The driving motor may be connected in different ways to the cutter head. As shown, the shaft 17 of the motor is equipped with a coupling sleeve 18 which may be threaded or otherwise fixed thereon, and this coupling sleeve is adapted to detachably receive the adjacent end of the sleeve 8 of the cutter head, a screw 19 or

other suitable means being employed for detachably securing and operatively connecting the sleeve 8 to the coupling sleeve 18. 65 The motor shaft 17 is preferably provided with an extension shaft 20 which extends longitudinally within the cutter head sleeve 8 and thus provides a strong and rigid support therefor. 70

The present invention provides a defroster which is relatively light in weight and capable of being manipulated with ease and facility to bring it into position for operation on the pipes or coils to be defrosted and to 75 handle it during its operation. The construction of the cutter head is such that the frost or frozen mixture will be removed quickly and efficiently as the knives are capable of removing the frost or frozen mixture by a cutting action and the frost or frozen mixture, as it is detached from the pipes or coils, is free to discharge from the cutter head, thus avoiding clogging. Moreover the manner in which the frost or frozen 80 mixture is cut from the pipes avoids scattering of the detached frost or frozen mixture, thereby avoiding distribution of the particles of detached frost or frozen mixture 85 among the food products undergoing refrigeration or in storage. The circumferential pitch of the knives produces a shearing action upon the frost or frozen mixture, thus 90 facilitating its removal. 95

I claim as my invention:—

1. A defroster for refrigerant pipes and coils comprising a revoluble outer member embodying a series of spaced apart, helical, radially shallow knives, said knives having cutting edges formed by two surfaces, one being a surface of revolution, and the other being dished and merging into said first surface, said dished surface forming a frost discharge member. 100 105

2. A defroster for refrigerant pipes and coils comprising a revoluble cutter member embodying a series of relatively fixed knives which are spaced apart and arranged spirally in the surface of a cone whereby said member is reduced in diameter toward one end, and operating means connected to the opposite larger end of said member. 110 115

3. A defroster for refrigerant pipes and coils comprising a revoluble cutter member embodying a series of relatively fixed knives which are spaced apart and arranged spirally in the surface of a cone, and a conical cage-like guard loosely mounted on said member and within which said member is 120 freely revoluble. 120

In testimony whereof I have hereunto set my hand.

MILTON W. BROWNE.
